UNITED STATES PATENT OFFICE.

RAYMOND H. MANLEY, OF COTTONWOOD, ARIZONA.

TOY VEHICLE.

Application filed July 5, 1923. Serial No. 649,606.

To all whom it may concern:

Be it known that I, RAYMOND H. MANLEY, a citizen of the United States, and resident of Cottonwood, in the county of Yavapai and State of Arizona, have invented 5 certain new and useful Improvements in Toy Vehicles, of which the following is a specification.

My invention relates to improvements in 10 toy vehicles of the class comprising vehicles which are adapted to be straddled by children and to be propelled by body movements of the riders, and it consists in the combinations, constructions and arrangements herein described and claimed.

An object of the invention is to provide a 20 vehicle of the character described which is constructed in such manner that a forward and backward rocking movement of the body of a child seated thereon will cause locomotion of the vehicle.

A further object of the invention is to provide a wheelless vehicle which is supported 25 upon rocker units which are adapted to be actuated successively upon forward and backward rocking movement of the body of a child seated on the vehicle to cause locomotion of the vehicle along a supporting surface.

30 A further object of the invention is to provide a vehicle of the character described which is relatively simple in construction, strong and durable, easy of operation and thoroughly practical commercially.

35 Other objects and advantages will be apparent from the following description, considered in conjunction with the accompanying drawings, in which—

40 Figure 1 is a side elevation of a vehicle embodying the invention, showing the forward end portion of the body of the vehicle in relatively raised position.

45 Figure 2 is a view similar to Figure 1, showing the rearward end portion of the body of the vehicle in relatively raised position, and

Figure 3 is a top plan view of the vehicle.

50 A vehicle embodying the invention in the form now preferred by me comprises a body which is designated generally 1 and which comprises an elongated seat 2, a pair of spaced bars 3 attached to the under side of the seat 2 and extending longitudinally of the latter, and a member 4 which is upstand-

ing from the seat 2 at the forward end of the latter and which carries a pair of laterally extending handles 5. The bars 3 are secured to the under side of the seat 2 to extend in parallel relation to each other and along the under side of the seat 2 adjacent to the opposite side or longitudinal edges of the latter, as best seen in Figure 3. The bars 3 extend beyond the forward end of the seat 2 and at points adjacent to their forward extremities support a pair of laterally extending foot rests 6 which may be the extending end portions of a single bar or rod, such as that indicated at 7, which extends through openings in the forward end portions of the bars 3 and is secured to the latter by pins 8 or like fastening means. In a like manner, the handles 5 may be the extending end portions of a single rod or bar which is supported intermediate its length in an opening through the upper part of the upstanding member 4 and extends equi-distant beyond the opposite sides of the latter.

The seat 2 and the bars 3 may be fashioned to have the general shape of the body of an animal, such as a horse, and the upstanding member 4 may be fashioned to have the shape of the neck portion and head of the animal, the likeness being accentuated by the use of paint on the upstanding portion 4 in 85 the manner indicated at 9, if desired.

The body 1 is supported adjacent to its forward end upon a rocker unit 10 and adjacent to its rearward end upon a rocker unit 11. The rocker unit 10 comprises a pair of similar rockers 10^a held in spaced parallel relation in respect to each other by a connecting block 10^b and provided with a pair of axially aligned trunnions 10^c which extend from opposite sides of the rockers 10^a in eccentric relation to the latter, the axis of the trunnions 10^c intersecting the rocker unit 10 along a line located nearer to the forward end of the rocker unit and nearer to the upper side of the rocker unit than to the rearward end and the lower side of the rocker unit 10, or in other words relatively adjacent to the upper front corner of the rocker unit. The trunnions 10^c are journaled in horizontally aligned openings 12 in the bars 3, the axis of the openings 12 lying in a vertical plane passing rearwardly of the handles 5. The lower and rearward faces of each of the rockers 10^a which respectively are indicated at 10^d and 10^e are 110

merged one into the other along a curved line and lie in planes extending substantially at right angles to each other.

The rear rocker unit 11 comprises a pair 5 of similar rockers 11^a held in spaced parallel relation in respect to each other and connected by a block 11^b, the rocker unit 11 being provided with a pair of trunnions 13 extending laterally of the remote faces of the 10 rockers 11^a. The axis of the trunnions 13 intersects the rocker unit 11 along a line relatively adjacent to the front upper corner of the rocker unit 11. The trunnions 13 are journaled in horizontally aligned openings 15 14 in the rearward end portions of the bars 3. The lower face of each of the rockers 11^a is indicated at 11^c and is relatively long, being convexly curved as shown and being merged along a curved line into the front 20 face 11^d of the rocker.

A spring 15 which is secured adjacent to its rearward end to the under side of the seat 2 curves downwardly and forwardly toward its front end and engages at its front 25 end with the upper side of the connecting block 10^b rearwardly of the vertical plane in which the axis of the trunnions 10^c is located, thus tending to swing the rocker unit 10 a clockwise direction about the axis of 30 the trunnions 10^c to the position illustrated in Figure 1, whereby the body 1 will be raised at its forward end. A spring 16 which is secured at or adjacent to its rearward end to the under side of the seat 2 35 curves downwardly and forwardly toward its forward end and engages at its forward end with the upper side of the block 11^b rearwardly of the vertical plane in which the axis of the trunnions 13 lies and tends to 40 swing the rocker unit 11 in a clockwise direction about the axis of the trunnions 13 to the position illustrated in Figure 2, whereby the rearward end portion of the body 1 will be raised in respect to a supporting surface, such as that indicated at 17, as shown 45 in Figure 2.

From the foregoing description of the various parts of the device, the operation thereof may be readily understood. The weight 50 of the body of a child who is seated upon the body 1 will hold the body 1 substantially in horizontal position so long as the body of the child is erect. In order to propel the vehicle, the child places his feet upon the 55 foot rests 6, grasps the handles 5 and then alternately bends the body forward and backward, pushing with his feet against the foot rests 6 and with his hands against the handles 5 during the forward movement of his body and pulling on the handles 5 during the rearward movement of his body. During the forward movement of the body 60 of the child, the pressure occasioned by his weight on the body 1 will be removed from the rocker unit 11 to an extent sufficient to

permit the spring 16 to act to swing the rocker unit 11 to the position shown in Figure 2. When the weight of the body of the child is imposed upon the rocker unit 11, as when the body of the child has been swung 70 backward, the action of the spring 15 will swing the rocker unit 10 to the position shown in Figure 1 and the rocker unit 11 will roll forward to a position in which the radial distance from the axis of the trunnions 13 to the supporting surface is relatively short, thus occasioning a movement of the body 1 over the supporting surface in the general direction of the length of the body 1 and in a manner simulating the 80 movement of an animal which walks on four legs.

It thus will be apparent that the radial distance from the axis of the trunnion of the rocker unit 10 to the supporting surface 85 will be relatively short when the radial distance from the trunnions of the rocker unit 11 is relatively long, and vice versa. Therefore, rocking of the body of a child who is seated upon the body 1 forward and backward will cause locomotion of the vehicle. This movement of the vehicle can be effected with but relatively little fatigue to the child and the movement of the vehicle in a forward direction can be guided by varying 90 the pressure against the respective foot rests 6, as required. The swinging movements of the rocker units 10 and 11 in response to the actuation thereof by the springs 15 and 16 will be limited by the engagement of the 95 rocker units with the under side of the seat 2. The vehicle comprises no parts which move relatively in such manner as to be likely to pinch or injure any portion of the body of the child who is seated thereon. The outer side faces of the rockers 10^a and 11^a may be painted to depict the legs and feet of the animal of which the upstanding portion represents the neck and head portion. 100

Obviously, my invention is susceptible of embodiment in forms other than that illustrated in the accompanying drawings and I therefore consider as my own all modifications and adaptations of the form of the device herein disclosed which fairly fall within the scope of the appended claims. 110

Having thus described the invention, what I claim is:—

1. A toy vehicle comprising an elongated seat, a pair of eccentrics rockingly supporting the seat upon a supporting surface at points adjacent to the opposite ends of the latter and in advance of and above the level of the transverse central lines of the eccentrics, handle members supported upon the seat above the forward end of the latter, foot rest members supported in advance of the forward end of the seat, and spring means arranged between said eccentrics and 120

the seat and acting continuously to urge said eccentrics toward such positions in respect to the seat that the radial line from the axis about which each eccentric rocks to the supporting surface will be relatively long.

2. A toy vehicle comprising a seat, a pair of spaced apart parallel bars secured to the under side of the seat and extending beyond the forward end of the latter, a pair of laterally extending foot rests carried by said bars adjacent to the forward ends thereof, an upstanding handle carrying member on the forward end portion of said seat, a pair of rocker units swingingly attached to said bars for supporting said seat at points adjacent to the forward and rear ends of the latter, each of said rocker units being attached to said bars to turn about an axis intersecting the upper forward portion of each rocker unit, and spring means carried by the seat and re-acting against the upper sides of the rocker units rearwardly of their

axes of revolution to urge the rearward end portions of the rocker units downwardly. 25

3. A toy vehicle comprising a pair of rocker units, an elongated body swingingly supported upon the rocker units, one of said rocker units being disposed beneath one end portion of said body and the other rocker unit being disposed beneath the opposite end portion of said body, each of said rocker units comprising an eccentric adapted to rock about an axis intersecting the respective eccentric in advance of and above the level of its transverse central line and extending at right angles to the direction of length of said body, said rocker units being adapted to be actuated successively by the shifting of weight on the body of the vehicle from one end portion of the body to the opposite end portion thereof while both of said rocker units rest upon a substantially flat surface and when so actuated repeatedly to propel the body forward.

RAYMOND H. MANLEY.
